JOHN H. A. GARMAN AND JOHN M. TRAVIS, OF ST. LOUIS, MISSOURI, ASSIGNORS TO MULTIPLEX FAUCET COMPANY, OF ST. LOUIS, MISSOURI, A CORPORATION OF MISSOURI

REGULATING-VALVE FOR AERATED BEVERAGES.

1,005.

Specification of Letters Patent.

Patented Jan. 26, 1909.

Application filed October 2, 1907. Serial No. 395,578.

To all whom it may concern:

Be it known that we, JOHN H. A. GARMAN and JOHN M. TRAVIS, citizens of the United States, residing at St. Louis, State of

Missouri, have invented certain new and useful Improvements in Regulating-Valves for Aerated Beverages, of which the following is a full, clear, and exact description, reference being had to the accompanying drawings, forming a part hereof.

Our invention has relation to improvements in valves for regulating the flow of carbonated and aerated beverages, and particularly carbonated-water employed at soda-water fountains; and it consists in the novel construction and arrangement of parts more fully set forth in the specification and pointed out in the claim.

In the drawings, Figure 1 is a vertical section of a refrigerator showing our device applied to a faucet mounted thereon; Fig. 2 is an enlarged longitudinal section of the valve in one of its extreme positions; Fig. 3 is a similar section with valve dropped to lowest position by reason of reduced pressure in the tank carrying the carbonated water; Fig. 4 is a cross section on the line 4—4 of Fig. 3; Fig. 5 is a top view of the valve; and Fig. 6 is a top plan of the strainer-tube and strainer carried thereby.

The object of our invention is to provide a valve which shall regulate the flow of carbonated-water to a faucet wherein such water and syrup are mixed before they are discharged into the tumbler or glass in which they are dispensed.

The object sought is to secure uniform quantities of water for a given quantity of syrup, and as a fresh soda-water tank delivers the water under greater pressure than a tank half or partially full, the quantity of water discharged upon turning on of the faucet will be greater at one stage of the tank than at another, so that a uniform mixture of water and syrup is impossible.

Our regulating valve accomplishes the end here sought, since it controls the flow of the carbonated water to the faucet at a rate of speed and in such quantities as will insure a uniform discharge under all circumstances.

In detail the invention may be described as follows:

Referring to the drawings, R, represents a refrigerator provided with an ice tank T, in

which is disposed the coil of a carbonated-water-supply pipe P leading through the bottom of the refrigerator to a "soda-water" tank (not shown).

S, represents a syrup receptacle which delivers the necessary quantity of syrup through the pipe a to the faucet A, which may be of any well known pattern, but preferably one in which the mixing of the water and syrup is effected inside the faucet. The water is supplied to the faucet through a pipe b which extends into the ice tank and is coupled to the valve-casing 1 of our improved regulating valve.

The upper end of the pipe P is coupled by means of a union 2 to the lower end of a tube 3 which in turn is screwed into the socket 1' forming an extension of the valve-casing 1, a polygonal formation or collar 4 being formed on the tube to which a wrench can be applied. The upper end of the tube 3 terminates in a reduced perforated extension or strainer 5 spaced a suitable distance from the inner walls of the socket. The socket 1' is provided with an inner terminal central tube or nozzle 6 which not only serves to deliver the carbonated water into the valve-casing 1, but forms a guide for the reciprocating tubular valve 7 mounted to reciprocate in the valve-casing. When the valve is in its lowest position it rests on the inner end of the socket 1' (Fig. 3), the nozzle 6 entering the base of the valve. The upper end of the valve terminates in a perforated stem 8 provided with lateral discharge openings 9, a conical valve-seat 10 being formed around the terminal perforation or port 11. In the upper end of the valve-casing 1 is a passage d which leads directly to the pipe b. The casing is secured in position to the roof of the refrigerator R by a screw 12 entering a socket 13 in the casing, or it may be secured in any other mechanical manner.

The operation of the valve may be described as follows: When a fresh and highly charged soda-water tank is coupled to the pipe P, and the faucet is turned on to draw the water and syrup flowing into the faucet through the pipes b and a respectively, a uniform quantity of syrup will be delivered to the faucet with each operation of the latter; but unless some provision be made to regulate the flow of water, more water will pass into the faucet when drawn from a fresh

tank than after the tank has been partially emptied, because the pressure of the gas within the tank gradually drops and the driving pressure on the water decreases.

5 With our invention the flow of water is substantially uniform because when the water tank is first drawn upon, the high pressure within it is sufficient to force the valve 7 to its seat (Fig. 2) compelling the water to flow 10 into the passage *d* through the relatively constricted passage 11 only. As the pressure within the tank drops, the valve will fall to its lowest position over the nozzle 6 (Fig. 3), the water now being free to discharge directly into the valve-casing not only 15 through the terminal constricted passage 11 of the valve but through the peripheral openings 9 as well, whence it flows unobstructedly into the passage *d* (Fig. 3). The result is 20 that the quantity of water delivered to the faucet is substantially uniform at all times as it must be obvious that a flow through a constricted passage under great pressure will approach a flow through both the constriction 11 and openings 9 at a lower pressure. The device regulates itself, the weight of the 25 valve being proportioned to prevailing pressures in soda-water tanks. Since the quantity of water is substantially uniform when

delivered to the faucet, the soda-water mixture will also be uniform.

Such features of construction as are shown but to which no specific reference is herein made are well known and a description thereof is unnecessary.

Having described our invention what we claim is—

A regulating valve for aerated beverages comprising a tubular casing having a terminal discharge opening, a central nozzle at the opposite end for injecting the beverage into the casing, a tubular valve adapted to engage the nozzle for the lowest position of the valve, an upper terminal seat on the valve having a central constricted passage and having peripheral openings below the seat, the latter openings being cut off from communication with the discharge opening of the casing for an elevated or seated position of the valve, substantially as set forth.

In testimony whereof we affix our signatures, in presence of two witnesses.

JOHN H. A. GARMAN.
JOHN M. TRAVIS.
